FIG. 4.

INVENTOR
George W. Dover
By Heratius E. Bellows

ATTORNEY.

UNITED STATES PATENT OFFICE.

GEORGE W. DOVER, OF CRANSTON, RHODE ISLAND.

LONG-BIT-TOOL HOLDER.

1,356,609.

Specification of Letters Patent. Patented Oct. 26, 1920.

Application filed May 4, 1920. Serial No. 378,882.

To all whom it may concern:

Be it known that I, GEORGE W. DOVER, a citizen of the United States, residing at Cranston, in the county of Providence and 5 State of Rhode Island, have invented certain new and useful Improvements in Long-Bit-Tool Holders, of which the following is a specification.

My invention relates to holders for bits 10 or similar tools adapted for use in the tool post of a lathe planer or other machine.

The essential objects of my invention are to afford accommodation for bits of unusual length; to apply the clamping pressure of 15 the holding bars to that portion of the bit upon which the greatest strain occurs; to direct the bit horizontally to the work rather than at an incline to the holder whereby the bit points directly to the center 20 without the assistance of the tool post rocker, thus insuring less grinding to attain the desired result; to clamp the bit at a point relatively close to where the work is taking place; and to attain these ends in a 25 simple and inexpensive structure.

To the above and related ends my invention consists in such parts and in such combinations of parts as fall within the scope of the appended claims.

30 In the accompanying drawings which form a part of this specification

Figures 1, 2, and 3, are a side elevation, a plan view, and an end view respectively of my novel holder, and

35 Fig. 4, a section of the same on line 4—4 of Fig. 1.

Like reference characters indicate like parts throughout the views.

In detail my holder comprises two bars 40 6 of similar form and dimensions, rectangular in cross section, and comprising shanks 7, and laterally curved enlarged portions or heads 8 adjacent the ends. The bars when no bit is mounted therein, rest 45 one against the other and have upon their contiguous faces longitudinally disposed rectangular channels 10 extending throughout their length. Both heads 8 are concentrically bored to form holes 12 and 13 respectively of uniform diameter.

A stud is provided for clamping the bars comprising a cylindrical head 18 slidably

in the holes 12 and 13 provided on one end with a circular head 19 abutting against the outer face of one bar, and having upon 55 its opposite end a stem 20 of reduced diameter provided with a thread 21. Upon the stem 20 is a nut 25 engaging a washer 26 resting upon the outer face of the adjacent bar. For the accommodation of the bit 28 60 there is provided in the body a diametrically disposed passage 30 which is of sufficiently greater dimensions to insure that the bit shall not contact with the body. This passage is therefore solely for clearance. 65

In use the bit is clamped between the bars, and rests in the channels 10. The clamping is effected by turning the nut 25. The relatively greater bearing area of the 70 bars at their head portions affords increased strength at that point, and the location of the binding means in the end of the bars adjacent the working end of the bit is in the best position for sustaining the 75 strain upon the holder. The structure of the stud is inexpensive, does not touch the bit, and is particularly effective. An extremely firm interengagement of the bars with the bit results. 80

I claim:

1. In a tool holder of the character described, elongated clamping bars provided with longitudinally disposed channels upon their adjacent faces adapted to embrace a 85 bit, a stud loosely mounted in the bars provided with a clearance opening to permit the passage of the bit, and means on the stud embracing the bars for clamping the bars upon the bit. 90

2. In a tool holder of the character described, unbent clamping bars comprising elongated shanks, and heads upon the ends of the shanks, said heads and shanks being provided with longitudinally disposed rectangular channels in their adjacent faces adapted to receive a bit between the shanks and heads, a stud loosely mounted in the heads provided with a clearance opening for the bit, and a clamping nut carried by 100 the stud. 95

In testimony whereof I have affixed my signature.

GEORGE W. DOVER.
